FILAMENTARY CATHODE ASSEMBLY

Lynn Goodale, Newark, and Lyle A. Backer, Den-
ville, N. J., assignors to Federal Telephone and
Radio Corporation, a corporation of Delaware

Application March 3, 1942, Serial No. 433,170

10 Claims. (Cl. 250—27.5)

This invention relates to filament construction and particularly to multistrand filaments used in vacuum tubes.

The object of the invention is to minimize deformations occurring in such filaments due to non-uniformity of expansion and contraction during heating and cooling of the filaments, in the operation of the vacuum tubes.

In high power vacuum tubes such as well-known water cooled types, it has been customary to provide multistrand filaments, usually in a multi-phase connection, to produce the high amount of electron emission required of such large tubes. Filaments have heretofore been connected in the well-known star relationship in which one end of each filament is connected to a neutral point and the other end to a source of heating voltage. Inasmuch as the neutral ends need not be connected to the power source, since no net current flows to or away from the neutral point, it has been the practice to locate the neutral point within the tube and close to the filaments; with the result that unneutral wire leads or supports from the filament have not been symmetrical with respect to the filament leads to the neutral point. It has been found that the unequal expansion and contraction under temperature changes of some of the filament leads or rods relative to others has caused an unsymmetrical sagging of the filaments so that they get out of line and even become short-circuited.

Applicants have avoided this difficulty in accordance with this invention by a symmetrical arrangement of each of the filament strands and their connecting conductors, so that the changes in temperature produce substantially equal expansions and contractions on either side of the points of symmetry. A related feature is the use of cooling fins in connection with filament connectors of greater length than others to compensate for the effect of the greater length. As a result, the unequal expansion and contraction of the metallic parts is avoided and the filaments keep their shape.

The invention will be understood from the following detailed description and the accompanying drawing, of which

Fig. 1 shows an elevation view, partially in section, of a filament arrangement in accordance with this invention.

Fig. 2 is an end view taken at line 2—2 of Fig. 1;

Fig. 3 is a sectional view taken at line 3—3 of Fig. 1;

Fig. 4 is another sectional view taken at line 4—4 of Fig. 1; and

Fig. 5 is another sectional view taken at line 5—5 of Fig. 1.

The drawing illustrates a multistrand filament, the particular arrangement shown being a six-phase star-connected filament supported from a vitreous re-entrant base portion 10 forming part of the envelope of a vacuum tube of the high power type. Only a portion of the tube envelope is shown, as the envelope and electrodes, other than the filament, constitute no part of this invention. The envelope will ordinarily be generally cylindrical in shape, part of this cylindrical portion being shown at 11. At the annular re-entrant portion 12, there are sealed through the glass, by long seals 13, a number of metallic supporting rods. Six of these supporting rods, namely 14, 15, 16, 17, 18 and 19 lead to respective ungrounded ends of six hairpin-shaped filaments 20, 21, 22, 23, 24 and 25, the two filaments 21 and 22 lying directly back of filaments 23 and 24, respectively in Fig. 1.

Some additional rods, for example three, 26, 27 and 28 are likewise sealed through the annulus 12, and these three rods are connected with, and support a platform comprising metallic disc 29. A second metallic disc 30 is supported in spaced relationship to disc 29 by rods 26, 27 and 28. These three rods are at neutral potential and will have connected to them the neutral terminals of the filaments. The six unneutral rods 14 to 19 inclusive, are passed through holes or openings in the neutral discs 29 and 30 so as not to touch these discs. Thus, rods 14 and 15 pass through opening 31 of disc 29, and through individual holes 32 and 33 of disc 30; rods 16 and 17 are passed through opening 34 in disc 29 and individual holes 35 and 36 of disc 30; and rods 18 and 19 are passed through opening 37 of disc 29, and individual holes 38 and 39 of disc 30. The circle along which the six un-neutral rods 14 to 19 and the three neutral rods 26 to 28 are spaced, preferably uniformly, at the glass seal is of larger diameter than the circle on which these same rods are located where they pass through discs 29 and 30; so these rods are bent to flare outwardly from just below disc 29 as indicated at 14a, 15a, 16a, 17a, 26a and 27a; the corresponding flares for the other rods not being shown. The circle along which all nine of these rods are spaced just above the seals 13, are preferably bound together for increased rigidity by a glass ring member formed by individual glass seals 40 tied each to the next by a sturdy web of glass 41.

There is fastened to disc 29, a set of six rods 42, 43, 44, 45, 46 and 47. These rods terminating at disc 29, as shown in Fig. 5, extend parallel to the rods 14 to 19, through respective holes 48, 49, 50, 51, 52 and 53 in disc 30, without touching this latter disc. All twelve rods 14 to 19, and 42 to 47 extending through disc 30 to the filaments are preferably equally spaced around a circle as shown in Figs. 3 and 4, and the upper ends of rods 42 to 47 connect with the ends of the respective hairpin filaments other than the ends to which rods 14 to 19 are connected.

Each of the six hairpin-shaped filaments is formed with a loop in the middle, providing a pair of substantially parallel arms of equal length. For the purpose of supporting the six hairpin filaments, there is provided a centrally located shaft 54 fastened at the middle of the platform 29 to which it may be attached as by welding, and closely fitted through the center of disc 30. This assembly of the platform 29 and disc 30 and shaft 54 is supported by rods 26, 27 and 28. The opposite end of shaft 54 supports at its end a disc 55 which has around its periphery, holes through which are placed respective insulating bushings 56, 57, 58, 59, 60 and 61. There is passed through each bushing a respective wire loop 62, 63, 64, 65, 66 and 67, the protruding ends of which are turned over as shown in Fig. 2 to hold each loop in its bushing. A positioning piece 68 may be placed over the top of the disc 55 and fastened as by screws 69, this positioning piece providing slotted tongues 70 which engage with corresponding grooves in the insulating bushings to keep them from turning.

The six hairpin-shaped filaments are looped through their respective supporting loops as shown, and the ends of the hairpins fastened to the respective rods 14 to 19 and 42 to 47 in a suitable manner, such as by thin metal sheaths 71 wrapped around the overlapping ends of the filament and rod, and fastened as by welding.

A cooling fin 72 is attached to each of rods 14 to 19 inclusive, to carry heat away from it.

By reason of this construction, the supporting platform 29, together with discs 30 and 55, the central shaft 54 and the rods 26, 27 and 28 are placed at neutral potential. The six filament connecting rods 42 to 47 are likewise at neutral potential, so that one end of each filament is neutral and the other end of each filament is unneutral for connection with a suitable source of filament voltage. This is the well-known six-phase star-connection. The source of filament heating voltage will be connected to the rods 14 to 19 protruding from the glass envelope; and the neutral potential rods 26, 27 and 28 may likewise be connected to ground outside the tube if desired.

In the operation of the tube, great heat is developed at the filaments and much of the heat is carried through the filament connecting rods 14 to 19, and 42 to 47. When the filaments are heated and cooled, there is a corresponding expansion and contraction of the filament strands and of these connecting rods. By reason of the fact that the substantially parallel sides of each filament strand are of equal length, and that the parallel filament connecting rods 14 to 19, and 42 to 47 extend for a substantial length, the expansion and contraction of the strand and connecting rod on each side of each filament loop is nearly the same so that unequal sagging does not occur; and after the filaments cool, they be-

come restored to substantially their original position.

Owing to the fact that the un-neutral rods 14 to 19 have some additional length through bends 14a to 19a, beyond the neutral connecting rods 42 to 47, there is some tendency for the rods 14 to 19 to expand, when heated, somewhat more than rods 42 to 47. This is compensated for by the cooling fins 72 placed on rods 14 to 19 just above platform 29. The fins are proportioned so that they carry away from rods 14 to 19 sufficient of the heat sent through them by the filament to cool them enough so that they do not expand and contract in the direction of the filament any more than rods 42 to 47.

What is claimed is:

1. A multistrand filament assembly comprising a plurality of filaments, each of which is a wire looped at the middle, individual supports on which the loops are supported, individual rods to which opposite ends of each filament are attached, a supporting platform to which one rod from each filament is fastened, the other rod from each filament extending past and out of contact with said platform and away from the region of highest temperature.

2. A multiphase filament assembly comprising a plurality of wire filaments looped at the middle and having the portions on either side of the middle loop extending nearly parallel, individual supports from which the middle loops are suspended, a plurality of substantially parallel rods, the individual ends of each filament being attached to an individual one of the rods, a supporting platform in a plane substantially perpendicular to the plane of the rods, the rod from one end of each filament being attached to said platform, the other rod from each filament extending as far as said platform but out of contact with said plate and being bent substantially at said platform to continue in a different direction, the last-mentioned rods being terminals of the multiphase filament.

3. A multistrand filament assembly comprising a centrally supported metallic shaft, a supporting means including a disc-shaped platform attached to said shaft, a plurality of filaments, each of which is in the form of a wire looped at the middle and arranged with an equal length of substantially parallel lengths on either side of the loop, each loop being supported from an individual support attached to said supporting means and insulated from each other and from the shaft, said parallel filament sides extending generally parallel to said shaft, individual terminal rods attached to opposite ends of each filament and extending in the same general direction parallel to said shaft, one rod from each filament being attached to said platform, the other rod from each filament extending through but insulated from said platform.

4. An assembly according to claim 3 in which said other rods are bent to take a different direction after passing through said platform.

5. A multiphase filament assembly comprising a plurality of filaments, conducting leads to each end of each filament, one lead to each filament being connected to a point common to all filaments and the other lead from each filament being connected to a source of polyphase heating voltage, each filament being symmetrically arranged with respect to its midpoint, and the conducting lead from the common point to each filament being of effectively equal length to the other conducting lead to each filament.

6. A multistrand filament assembly comprising a plurality of filaments, each of which is looped at its middle and has the portions on either side of the loop extending substantially parallel and of equal length, a pair of conducting leads connecting to the respective ends of each filament, one lead of each pair connecting to a common point and the other lead of each pair connecting to a source of heating voltage, said other leads extending substantially parallel to the leads connected to the common point for the greater part of the length of said leads.

7. A multistrand filament assembly comprising a plurality of filaments, each of which is looped at its middle and has the portions on either side of the loop extending substantially parallel and of equal length, a pair of conducting leads connecting to the respective ends of each filament, one lead of each pair connecting to a common point and the other lead of each pair being connected to a source of heating voltage, said other lead extending substantially parallel to the lead connected to the common point as far as said common point, said other lead being bent out of line from said parallel direction adjacent said common point of connections.

8. A multistrand filament assembly comprising a plurality of filaments, each of which is looped at the middle to form a hairpin-like shape with the portions of the filament on either side of the loop extending substantially parallel to each other and of equal length, means spaced around a circle for supporting each filament at its loop, individual rods connected with opposite ends of each filament and extending in the general direction of said filament to which it is connected, said rods being spaced around a circle

5 and being substantially parallel with each other, a metallic connecting means for acting as a common potential point, there being one of the rods from each filament connected to said metallic connecting means, the other rod from each filament being bent out of said parallel direction at a place adjacent said connecting means and connected therebeyond to a source of filament heating voltage.

10 9. A multistrand filament assembly comprising a plurality of filaments, each of which is looped at the middle and has the portions on either side of the loop extending substantially parallel and of equal length, a pair of conducting leads connected to the respective ends of each filament, a first lead of each pair connecting to a common point and the second lead of each pair extending substantially parallel to and past the end of the first lead, and a cooling fin connected to the second lead and proportioned to conduct enough heat away from the second lead so that said second lead expands and contracts relative to the filament to the same extent as the first lead.

15 10. A filament assembly comprising a filament looped at its middle and having portions on each side of the loop extending substantially parallel and of equal length, an individual conducting lead connected to each end of the filament, said leads extending substantially parallel but of unequal length, and a cooling fin connected to the longer one of said leads, said cooling fin being proportioned to conduct away enough heat from the longer heat so that both leads expand and contract relative to the filament under temperature changes, to substantially the same extent.
